Primary Examiner — Sandra Snapp*(74) Attorney, Agent, or Firm* — Faegre Baker Daniels LLP**CLAIM**

The ornamental design for a lounge, as shown and described.

DESCRIPTION

FIG. 1 is a front perspective view of an end portion of a lounge according to our new design, the lounge including an armrest cap;

FIG. 2 is a front view thereof;

FIG. 3 is a rear view thereof;

FIG. 4 is a right side view thereof; and,

FIG. 5 is a top view thereof.

Features shown in broken lines form no part of the claimed design.
